THREAD WINDING APPARATUS

Ellsworth M. Wilson, Snyder, N. Y., assignor to
E. I. du Pont de Nemours & Company, Wil-
mington, Del., a corporation of Delaware

Application December 22, 1936, Serial No. 117,174

4 Claims. (Cl. 242—46.2)

This invention relates to improved apparatus for the winding of thread, and more particularly it relates to apparatus for removably mounting a bobbin or spool on a rotatable spindle. The present invention has particular utility in the spinning of artificial silk.

In the spinning of artificial silk, for example, from a viscose solution, the freshly coagulated thread is wound on to a foraminous or perforated bobbin on which it may subsequently be subjected to a purifying operation. The bobbin is customarily removably mounted on a rotating spindle. In order to maintain a uniform tension on the freshly formed thread as it is being drawn from the spinneret, it is necessary to position the bobbin concentrically of the axis of the rotating spindle and prevent slipping of the bobbin relative to the spindle. The bobbin must furthermore be removably positioned on the spindle in such a manner that a full bobbin can be quickly removed and an empty bobbin substituted therefor.

It is therefore an object of the present invention to provide an improved bobbin-holding mechanism which will permit ready exchange of bobbins on a spindle.

It is a further object of the present invention to provide an improved bobbin-holding mechanism which will permit a ready exchange of bobbins on a spindle and which will hold the bobbin concentric to the axis of the spindle without substantial slippage relative thereto.

Other objects of the invention will appear hereinafter.

The various advantageous features of the present invention will be more clearly apparent by reference to the following detailed description taken in connection with the accompanying illustrations, in which:

Figure 1 is a side elevational view showing a bobbin in position on a bobbin-holding device constructed in accordance with the invention.

Figure 2 is a vertical cross-sectional view of the bobbin-holding device shown in Figure 1.

Figure 3 is an end view of the bobbin-holding device shown in Figure 2.

Figure 4 is a cross-sectional view taken along line 4—4 of Figure 2.

Figure 5 is an end view of the bobbin-holding device of Figure 2 with the cap removed.

Referring to the drawings, reference numeral 11 designates a rigid base support which is provided with a centrally positioned opening for reception of the rotatable spindle 13. The spindle is provided with a flanged shoulder portion 15 against which the base support 11 may rest. The

base support 11 has a flange 17 and a plurality of longitudinal grooves 19. The grooves 19 extend into the flange 17 thus providing shoulder 21 for holding one end of the bobbin contacting member 23. The base support 11 is preferably provided with a number of depressions or counter sunk portions 25 which are adapted to cooperate with projection 27 of the bobbin contacting members. The bobbin contacting members are provided with a number of counter sunk portions 29 in which may be positioned resilient elements 31 or 33, which elements may be composed of rubber or any other resilient material or may be springs of any desired configuration so as to resiliently support the bobbin contacting members 23. In the device 15 illustrated, the resilient members are constructed of rubber. Two of the four bobbin contacting members illustrated are provided with solid rubber elements 31 which have a relatively small amount of resiliency, and two of the members 23 20 are provided with rubber elements 33 having perforations therein so as to cause them to yield much more readily than the rubber elements 31. It will thus be obvious that two of the bobbin 25 contacting members 23 will be considerably more yieldable than the other two contacting members. The advantage of having two of the bobbin contacting members more yieldable than the other two similar members is to prevent an eccentric 30 positioning of the bobbin on the bobbin holding device as will appear hereinafter.

The bobbin contacting members are arranged with one end thereof positioned back of shoulder 21 and the other end thereof held in place by means of a cap 35. As will be noted from Figure 4 of the drawings, the cap 35 is provided with grooves 37 which grooves are enlarged at the base thereof as is illustrated by the offset portion 39. These offset grooves are adapted to fit about the bobbin contacting members 23 and particularly the lugs 41 of the said contacting members so as to prevent the contacting members from being removed from the grooves 19. The cap 35 is provided with a projecting lip which covers the ends of members 23 and thereby holds the latter in the base support 11. The base support 11 is provided with a plurality of projecting members 43 (see Figure 2) which projecting members have circular notches 45 in which may be positioned an annular rubber ring of circular cross section. The cap 35 is also provided with circular notches which may be aligned with the circular notches 45 so that the annular rubber ring of circular cross section will fit within the notches of extension 55

members 43 and the notches of cap 35 to securely hold the cap and base support together.

It is preferred that the notches cut into flange 17, whereby to provide the shoulders 21 for retaining the bobbin contacting members, be cut with a greater radius for the bobbin contacting members provided with the more yieldable rubber retaining means 33 than for the contacting members provided with the less yieldable solid rubber supporting means 31. This is clearly shown in Figure 2 of the drawings in which the shoulder 21, adapted to hold the bobbin contacting member which is provided with the perforated yieldable supporting means 33, is thinner than the shoulder 21 adapted to hold the other bobbin contacting member. The latter shoulder 21 is positioned to hold its contacting member at a distance from the longitudinal axis of the spindle substantially equal to the inside radius 20 of the bobbin. This will obviously permit the bobbin contacting members supported by the perforated yieldable element 33 to be thrust outwardly from the axis of the spindle a greater distance than the other contacting members. Therefore, in placing the bobbin 47 on the bobbin holding means, the contacting members which are positioned on the more resilient means 33 are pushed inwardly whereas the other bobbin contacting members remain substantially stationary, thus holding the bobbin concentric to the longitudinal axis of spindle 13. This permissible movement of two of the bobbin contacting members is clearly illustrated in Figure 4 of the drawings by dotted lines. It is preferred to have the members 31 slightly yieldable so that a bobbin which is bent slightly out of shape may be forced onto the bobbin holding means.

The base support 11, the bobbin contacting members 23, and the cap 35 may be made of any desirable material which will be inert to treating liquids used in the treatment of artificial silk fibers. They may, for example, be constructed of hard rubber, resin condensation products, aluminum or other metal or metal alloys. The yieldable members 31 and 33 may be constructed of any yieldable material, it being preferred that the members in some of the contacting members be more yieldable than the others. Instead of perforating the relatively dense, non-yieldable, rubber block in order to make it yieldable, a more yieldable rubber such as, for example, sponge rubber, may be used in which case it need not be perforated or may be perforated with a smaller number of perforations.

Bobbin-holding devices constructed in accordance with the present invention are adapted to maintain a uniform tension on a bobbin and

to maintain the bobbin concentrically of the axis of the rotating spindle. The bobbin contacting means has sufficient surface to prevent slipping of the bobbin relative to the spindle, and at the same time has sufficient yieldability to easily remove the bobbin from the bobbin-holding device when desired. This yieldability can easily be varied by substitution of blocks of different density or elasticity.

Inasmuch as many obvious changes and modifications can be made in the above detailed description without departing from the nature and spirit of the invention, it is to be understood that the invention is not to be limited except as set forth in the appended claims.

I claim:

1. In a bobbin holder, a base support, means for mounting said support on a spindle, a plurality of resiliently supported bobbin contacting members, some of said contacting members having supports of greater resiliency than the other contacting members, whereby to aid in holding a bobbin concentrically of said spindle.

2. In a bobbin holder, a base support, means for mounting said support on a spindle, a plurality of radially movable bobbin contacting members positioned in said base support, yieldable members of varying yieldability so constructed and arranged between said support and said contacting members as to permit the various contacting members to move radially inwardly different distances by the positioning of a bobbin on said holder.

3. In a bobbin holder, a rigid base support, means for mounting said support on a spindle, a plurality of radially movable bobbin contacting members positioned in said base support, a plurality of yieldable members positioned between and in contact with the base support and each of said contacting members, the yieldable members positioned in contact with some of said contacting members having a greater resiliency than the yieldable members positioned in contact with the other contacting members.

4. In a bobbin holder, a base support, means for mounting said support on a spindle, a plurality of bobbin contacting members mounted in said support, said contacting members radially movable relative to said support, a plurality of yieldable members positioned between said support and each of said contacting members, at least one of said contacting members being mounted with greater permissible radial movement and being provided with yieldable members of greater yieldability than the remaining contacting members.

ELSWORTH M. WILSON.
